Specification for Design.

Patented Apr. 8, 1913.

Application filed October 5, 1912. Serial No. 724,223. Term of patent 14 years.

To all whom it may concern:

Be it known that we, JAMES PAULL and JESSE L. FUSNER, citizens of the United States, both residents of Wellsburg, Brooke county, West Virginia, have invented a new, original, and ornamental Design for Watch-Shaped Receptacles, of which the following is a specification, reference being had to the accompanying drawing, forming part hereof, in which the figure is a perspective view of a receptacle embodying our design.

We claim:

The ornamental design for a watch-shaped receptacle, as shown.

In testimony whereof, we have hereunto set our hands.

JAMES PAULL.
JESSE L. FUSNER.
